UNITED STATES PATENT OFFICE.

JOHN H. LUDWIG AND CHARLES A. ERICSSON, OF NEW YORK, N. Y.

UPRIGHT-PIANOFORTE ACTION.

SPECIFICATION forming part of Letters Patent No. 515,152, dated February 20, 1894.

Application filed October 26, 1893. Serial No. 489,166. (No model.)

To all whom it may concern:

Be it known that we, JOHN H. LUDWIG and CHARLES A. ERICSSON, citizens of the United States, residing in the city, county, and State 5 of New York, have invented certain new and useful Improvements in Upright-Pianoforte Actions, of which the following is a specification.

The object of our invention is to improve 10 the repeating action in an upright piano, simplifying it and economizing both space and material.

The accompanying drawing which forms a 15 part of this specification, represents in elevation our improved action in normal position.

The key is shown at 1 and is pivoted in any preferred way.

2 is the abstract fastened by pin to the jack 3 on the key 1. At the upper end the abstract 20 2 is pinned or otherwise securely fastened to the rocker 4 which is pivoted to flange 5 carried by rail 6. The jack 7 is pivoted to the outer end of the rocker 4. 8 is the flange on said rocker to which is pivoted the escapement lever 9. One part of our invention consists in prolonging upward this flange and adapting it to act as a back check. We make 25 the back check more responsive by making a saw-cut or slit in its upper end as shown at 10. The said upper end is covered with felt or 30 cloth 11.

12 is the jack stop screw supported in the flange 8.

13 is the adjusting screw for the escapement lever and 14 is the regulating screw for 35 said lever supported in the rail 15.

16 is the hammer whose rod 17 rests normally against the felt of rail 18 and whose butt 19 is pivoted on flange 20 of rail 21.

40 22 is the roll cushion interposed between the escapement lever 9 and the hammer butt 19. These two parts, to wit, the hammer butt and the escapement lever, are connected by spiral spring 23 and silk thread 24, these two 45 parts being united together and forming a close but yielding connection between the escapement lever and the hammer preventing any considerable separation of the two and insuring the rapid drawing back of the hammer after the blow has been delivered to the string. Thus, the lever and butt act in unison without any waste motion just as if they were

one. A wire hook 44 serves as the means of attaching the silk thread loop 24 to the hammer butt.

55

25 is the back stop supported on the butt 19 by the wire 26 and acting against the flange 8.

It will be seen that we make the flange 8 permanent and rigid and any adjustment that is necessary for an individual key is made by 60 means of the wire 26 which course is the reverse of that usually adopted in former actions.

27 is the spring which holds up the escapement lever and operates on the heel 28 of jack 7. 65

29 is the jack regulating screw which we mount in the manner shown, that is to say, we arrange it diagonally in the lower edge of the rail 21 so that its operative end projects forward in convenient position to be operated 70 by means of a screw driver, or otherwise. By this means considerable economy of space is effected.

30 is the pad which stops the jack when it has moved to the required distance. 75

The string is shown at 31, a damper at 32, a damper lever at 33 pivoted on the flange 20 and a damper lever rocker at 34 pivoted on the flange 35 carried by rail 36. The rocker 34 has a spoon or rod 37 which bears on a pad 80 at the lower end of the damper lever 33.

38 is a step on the abstract preferably made with the inclined upper face as shown to receive a pad 39 on the under front end of the damper lever rocker 34. 85

40 is the sustaining pedal bar. The sustaining pedal is not shown but it is understood that the usual means of rocking this bar may be employed. The bar stretches across the piano over the entire length of the 90 dampers and is fastened in the action brackets so as to be capable of being revolved by means of the pedal.

41 is a spring hook supported in the end of the damper lever rocker 34. When the rocker 95 34 is raised on depression of the key 1, the spring hook 41 is engaged and held by the bar 40 which is turned up by the foot to engage it so that any individual note may be held and sustained independently of the others by 100 reason of its damper being held away from the spring by the action of the spoon 37 acting on the lower end of the damper lever 33 until released from the bar 40 by the action

of the pedal. The lack of positive connection between the step 38 and the cushion 39 allows this independent operation of the rockers 34.

5. It will be seen that the action is positively connected together all the way from the key to the hammer, operating throughout without loose motion, for the abstract is connected positively at its two ends to the key and the 10 rocker, and the escapement lever which is supported by flange 8 on said rocker is connected by the spring 23 and silk thread 24 with the hammer butt. There will thus be no separation at any of the joints during the 15 movement of the action.

Having thus described our invention, the following is what we claim as new therein and desire to secure by Letters Patent:

1. In an upright pianoforte action, the 20 rocker 4 having flange 8, the escapement lever 9 carried by said flange, the upper end of said flange being prolonged and adapted to act as a back check in combination with the hammer and the stop or check 25 carried 25 thereby and having its inner side engaging said back check, substantially as set forth.

2. The combination of the rocker 4, the escapement lever 9, the rigid combined flange and back check 8, the hammer and the back 30 stop 25 supported by flexible rod 26 from the hammer butt, substantially as set forth.

3. The combination of the rocker 4, the escapement lever 9, flange 8 prolonged above

said lever and having its upper end slit or saw-cut and hammer and back stop adapted 35 to act in connection therewith, substantially as set forth.

4. The combination of the rocker 4, the escapement lever 9, jack 7, the hammer, the roll cushion 22 interposed between the hammer 40 butt and escapement lever and a tension spring connected to the escapement lever and to said hammer butt, substantially as set forth.

5. The combination of the rocker 4, the escapement lever 9, jack 7, the hammer, the roll 45 cushion between the hammer butt and escapement lever, the tension spring 23 and silk thread 24, said spring and thread being connected together and serving to unite the escapement lever and hammer butt, substantially as set forth.

6. In an upright pianoforte action having the rocker 4 and the abstract 2 connecting said rocker with the key without loose motion, the upright damper lever 33, the horizontal damper operating rocker 34, the step 38 on the abstract whereon the forward end of said damper operating rocker rests, hook 41 on said damper operating rocker and a sustaining bar 40, arranged to operate substantially as set forth.
